UNITED STATES PATENT OFFICE.

JUDSON L. MCKELLAR, OF BROOKLYN, NEW YORK, ASSIGNOR TO GASAU-THOMPSON COMPANY, INC., OF BROOKLYN, NEW YORK, A CORPORATION OF NEW YORK.

BEDSTEAD.

1,207,187.

Specification of Letters Patent.

Patented Dec. 5, 1916.

Application filed February 2, 1916. Serial No. 75,671.

To all whom it may concern:

Be it known that I, JUDSON L. MCKELLAR, a citizen of the United States, and a resident of Brooklyn, in the county of Kings 5 and State of New York, have invented certain new and useful Improvements in Bedsteads, of which the following is a specification.

The invention pertains more particularly 10 to the character of beds commonly called divans and comprises, with the other features of a bed of this character, novel means for securing the corner legs, my invention providing means for very conveniently and 15 firmly securing the corner legs either in their vertical operative position or in position folded under the bed.

It is desirable to economize space both in 20 shipping and storing the beds by having the legs of the beds folded inwardly under the spring, and several means for attaining this general result are well known.

My invention provides novel means capable of convenient use for locking the legs 25 in either of their two positions and these means are of extreme durability and they are also convenient to manufacture and assemble and add little to the cost of the bed.

The bed as a whole comprises tubular side 30 rails, malleable iron arms turning inwardly and downwardly and secured at their lower ends upon the ends of said side rails, angle iron bars secured to and connecting said arms at the head and foot of the bed and 35 receiving the end portions of the mattress supporting spring and leg mechanism, each comprising a tubular body portion, a T-coupling to which the leg is riveted and which is rotatable and slidable on the side rail of 40 the bed, a segmental plate cast with said coupling and normally extending upwardly and inwardly and having a segmental slot and a socket at each end thereof and a hub cast with the corner arm of the bed and providing a screw entered within the slot of 45 said segment and receiving a nut for binding said segment against the end of said hub, said hub at its end being adapted to the sockets in the end portions of said segment 50 and said nut and screw serving as means for binding the segment against said hub in either of the two positions of the leg.

As aforesaid my invention resides more particularly in the means provided for securing the legs of the bed in their vertical

and folded-in positions, and the said invention will be fully understood from the detailed description hereinafter presented, reference being had to the accompanying drawings, in which:

Figure 1 is a side elevation of a divan embodying my invention, the supporting legs being shown in their vertical operative position; Fig. 2 is an end view of the same; Fig. 3 is a view corresponding with Fig. 2 but illustrating the legs as having been folded inwardly under the main body of the divan; Fig. 4 is a sectional view, on a larger scale, through a portion of the divan taken on the dotted line 4—4 of Fig. 1, the supporting leg in this view being shown as locked in its vertical operative position; Fig. 5 is a side elevation, partly broken away, of that portion of the divan shown in Fig. 4 in transverse section; Fig. 6 is a view, partly broken away and on a larger scale and partly in section, of that portion of the bed illustrated in Fig. 5, Fig. 6 showing the nut as having been loosened and the segment connected with the leg as having been slid from the hub on the corner casting preparatory to the turning of the leg under the bed, and Fig. 7 is a sectional view, through a portion of the bed, taken on the dotted line 7—7 of Fig. 6, the screw being omitted.

In the drawings, 10 designates the tubular side rails of the divan, 12 the cast corner arms secured on the ends of said side rails, 13 angle bars secured to and connecting said corner arms and supporting the usual mattress-supporting spring or fabric, and 14 the supporting legs which will be of tubular formation and secured at their upper ends within the vertical members 15 of couplings 16 having horizontal tubular members 17 strung upon the side rails 10 and capable of rotary and also sliding movement thereon. The coupling members 16 will preferably be malleable castings and the members 15, 17 thereof form what is in effect a T-coupling, and upon the member 17 of each coupling 16 is cast a segmental plate 18 having a segmental slot 19 and normally extending upwardly and inwardly from the said member 17. The plates 18 at the ends of the slots 19 are formed with recesses 20 which afford inwardly beveled walls forming seats for the outer tapered ends 21 of hubs 22 which are cast with the corner arms 12 and have

at their outer tapered ends 21 horizontal screws 23 each extending through the slot 19 of a coupling member 16. Upon the outer ends of the screws 23 are provided thumb nuts 24. Each corner arm 12 is equipped with one of the hubs 22 and screws 23 and each leg 14 is equipped with one of the coupling members 16 having the plate 18. When the legs 14 are to be held in operative position, referring to Fig. 6 for convenience of explanation, the coupling 16 carrying the leg and plate 18 will be slid outwardly on the rail 10 until the tapered recess at the upper end of the slot 19 passes upon the tapered end of the hub 22 and thereupon the nut 24 will be tightened on the screw and against the plate 18 so as to secure the coupling member in position with the end of said hub and the tapered walls of said recess in interlocking relation. It will be evident that when the end of the hub 22 is within the upper recess of the plate 18 and the nut 24 screwed home against the plate 18, the leg will be securely held in vertical position, then being incapable of turning on the rail 10 or of sliding on said rail. When it is desired to fold the legs under the divan, the nuts 24 will be loosened and the coupling members 16 will be slid inwardly from the corner arms 12 or to about the position shown in Fig. 6, thereby freeing the upper recesses 20 from the projecting ends of the hubs 22, thereupon the legs may be folded under the divan or to the position illustrated in Fig. 3, the slot 19 of each plate 18 riding on the screw 23 and serving at its end as a stop, in connection with the screw, for arresting the leg when reaching its proper folded position. As each leg 14 is folded under the divan, the coupling 16 thereof will be slid outwardly toward the adjacent corner arm 12 so that the recess 20 at the end of the slot 19 may pass upon the tapered end of the hub 22 and when this has been done the nut 24 of each leg will again be tightened so as to secure the plate and hub in interlocking relation, the legs thus being locked in their folded position. The ends of the slots 19 of each plate 18 serve as stops to arrest the leg in its two extreme positions and in position to have one or the other recess 20 moved directly upon the hub 22 preparatory to the tightening of the nut 24.

My invention is applicable to several known characters of couch beds, of which the divan shown in the drawings is an example.

What I claim as my invention and desire to secure by Letters-Patent, is:

1. In a bed of the character described having side rails, and corner-arms secured to the ends thereof and extending upwardly therefrom, in combination, supporting legs for the bed, T-couplings rotatable on said side

rails and having their vertical members secured to the upper ends of said legs, plates rigid on the horizontal members of said couplings and having segmental slots, hubs on said arms having longitudinally extending screws passing through said slots, and nuts on said screws for binding said plates against said hubs.

2. In a bed of the character described having side rails, and corner-arms secured to the ends thereof and extending upwardly therefrom, in combination, supporting legs for the bed, T-couplings rotatable on said side rails and having their vertical members secured to the upper ends of said legs, plates rigid on the horizontal members of said couplings and having segmental slots, hubs on said arms having longitudinally extending screws passing through said slots, and nuts on said screws for binding said plates against said hubs, said plates at the ends of the slots therein having recesses to receive and interlock with the outer ends of said hubs on the tightening of said nuts.

3. In a bed of the character described having side rails, and corner-arms secured to the ends thereof and extending upwardly therefrom, in combination, supporting legs for the bed, T-couplings rotatable on said side rails and having their vertical members secured to the upper ends of said legs, plates rigid on the horizontal members of said couplings and having segmental slots, hubs on said arms having longitudinally extending screws passing through said slots, and nuts on said screws for binding said plates against said hubs, said plates at the ends of the slots therein having inwardly tapered recesses to receive and interlock with tapered outer ends of said hubs on the tightening of said nuts.

4. In a bed of the character described having side rails, and corner-arms secured to the ends thereof and extending upwardly therefrom, in combination, supporting legs for the bed, T-couplings rotatable on said side rails and having their vertical members secured to the upper ends of said legs, plates rigid on the horizontal members of said couplings and having segmental slots, hubs on said arms having longitudinally extending screws passing through said slots, and nuts on said screws for binding said plates against said hubs, each of said plates at the end of its slot having a recess to receive and interlock with the outer end of the adjacent hub on the tightening of the nut therefor.

5. In a bed of the character described having side rails, and corner-arms secured to the ends thereof and extending upwardly therefrom, in combination, supporting legs for the bed, T-couplings rotatable on said side rails and having their vertical members secured to the upper ends of said legs, plates rigid on the horizontal members of said cou-

plings and having segmental slots, hubs on said arms having longitudinally extending screws passing through said slots, and nuts on said screws for binding said plates against said hubs, said plates at the ends of their slots and the outer ends of said hubs being adapted to interlock with each other on the tightening of the nuts, to resist rotary movement of said couplings and legs.

- 10 6. In a bed of the character described having side rails, and corner-arms secured to the ends thereof and extending upwardly therefrom in combination, supporting legs for the bed, T-couplings rotatable on said 15 side rails and having their vertical members secured to the upper ends of said legs, plates rigid on the horizontal members of said cou-

plings and having segmental slots, hubs on said arms having longitudinally extending screws passing through said slots, and nuts 20 on said screws for binding said plates against said hubs, said plates being of segmental outline and cast with said couplings, and said hubs being integral with said corner-arms and extending horizontally there- 25 from.

Signed at New York, in the county of New York, and State of New York, this 17th day of January, A. D. 1916.

JUDSON L. McKELLAR.
